WINDOW ATTACHMENT

Adell Santrey, New York, N. Y.

Application June 9, 1941, Serial No. 397,323

2 Claims. (Cl. 292—76)

This invention relates to a window attachment and more particularly to a device which may take the place of sash weights and is adapted to be applied between a window sash and side portions of the window frame and serve very effectively to yieldably resist movement of the sash vertically in the window frame. It will thus be seen that use of sash weights and cords to counterbalance the weight of a window sash and hold it in raised position will not be necessary. This not only eliminates the use of weights and cords and the expense of frames having weight boxes at their sides, but also eliminates likelihood of a person being injured by a sash dropping from raised position due to the sash cords becoming frayed and broken.

One object of the invention is to provide a device which may be easily applied to a mounted window sash between side rails thereof and side portions of the frame, the device being formed of resilient metal and placed under tension when applied so that it has frictional engagement with the window frame and serves to firmly but yieldably hold the sash in vertically adjusted position.

Another object of the invention is to so form the spring that while it is initially of substantially bowed formation, it assumes a multiple curvature when subjected to flattening compression and fitted into place between the window sash and the window frame. This causes the spring to be placed under such tension, when applied for use, that teeth at its ends will be embedded in the sash and cause the spring to move with the sash as the sash is raised or lowered, the intermediate portion of the spring having such frictional engagement with the confronting portion of the window frame that it will be impossible for the sash to move downwardly by its own weight.

Another object of the invention is to provide a device of this character consisting of a strip of spring steel having its end portions disposed at such an angle that teeth at ends of the strip may have spurs at their extremities firmly embedded in the sash by pressure exerted when the strip is compressed and placed under tension.

In the accompanying drawing:

Fig. 1 is a view showing window holders of the improved construction applied between a window sash and a side portion of a window frame.

Fig. 2 is a view on the line 2—2 of Fig. 1.

Fig. 3 is a view showing a portion of Fig. 2 on an enlarged scale.

Fig. 4 is a transverse sectional view on an enlarged scale, on the line 4—4 of Fig. 2.

Fig. 5 is a perspective view of a sash holder or spring of the improved construction.

The sash holders constituting the subject matter of this invention are to take the place of sash weights and are applied as shown in Figs. 1 and 2, and, referring to these figures, it will be seen that they are inserted between side portions of the upper and lower sashes 1 and 2 and the retainer strips 3 and 4 of the sash 5 where they are confined under tensioning pressure and urge the sashes toward the parting bead or strip 6 so that frictional grip is established between the sashes and the dividing strip 6, as well as between the sash holders and the retaining strips. This frictional grip is such that sliding of the sashes by their own weight in the tracks 7 and 8 will be prevented and when a sash is shifted vertically in the frame to adjusted position, it will remain in adjusted position. Therefore, the use of sash weights and sash cords connecting the weights with the sashes will be eliminated and, also, it is not necessary to use an expensive window frame formed at its sides with weight boxes.

The holders or retainer springs are indicated 25 in general by the numeral 9 and while upper and lower springs are usually applied at each side of each sash, it is to be understood that additional springs may be applied to large, heavy sashes if found necessary. It will also be understood that 30 springs may be applied between the side edge faces of the sashes and confronting faces of the tracks 7 and 8.

The sash holders or springs are each of the 35 construction shown in Fig. 5. Referring to this figure, it will be seen that each holder consists of a strip of spring steel of suitable length and width. This strip has its end portions serrated to form a plurality of teeth 10 having their terminals or extremities bent to form spurs 11 40 which are comparatively short but of sufficient length to bite into the sash at an angle to the direction in which the teeth penetrate the sash when the spring or holder is in use and applied to a sash. The strip of spring steel is operated 45 upon in a die so that it is bowed for the major portion of its length but its end portions 12 are flat and extend straight from terminals 13 of the bowed portion at an angle thereto. The teeth 10 extend in the planes of the straight end 50 portions. The fact that the spring is bowed for the major portion of its length and is provided with straight end portions constituting integral extensions of the bowed portion is very important as this formation causes the spring or holder 55 to assume the shape disclosed clearly in Fig. 3,

when subjected to depressing pressure. Referring to this figure, it will be seen that when the spring is depressed by flattening pressure and slipped into place between a sash and a retainer strip of a window frame, the initially bowed or arcuate portion of the spring strip is transformed to provide outwardly curved gripping portions 14 having their inner ends connected by an upwardly curved intermediate portion 15 and their outer ends merging into the straight end portions 12 of the spring. The curved portions 14 and 15 of the spring cooperate with each other to exert high pressure and not only force the teeth and their spurs into the sash but also cause the segmental portions 14 to have such close contacting engagement with the confronting face of the window frame that sufficient frictional grip will be exerted to hold the sash in adjusted position in the frame. This pressure and frictional grip makes it unnecessary to provide sash weights and also causes the teeth and their spurs to so engage the sash that the spring cannot move out of the position in which it is applied to the sash. Therefore, the spring will travel with the sash during raising or lowering thereof and springs applied to the sash will remain in predetermined spaced relation to each other and in predetermined relation to ends of the sash.

In addition to eliminating the use of sash weights, the springs also serve to eliminate the use of weather strips for a window. This is due to the fact that the springs press the sashes firmly against side faces of the parting strip and eliminate spaces through which air may pass.

Having thus described the invention, what is claimed is:

1. A sash holder adapted to be fitted between a side portion of a window sash and a confronting surface of a window frame and anchored to the sash, said holder comprising a strip of spring metal bowed longitudinally for the major portion of its length and having straight end portions constituting integral extensions of the bowed portion and having anchoring teeth at their free ends spaced outwardly from the junctions of the straight end portions with ends of the bowed portion.
2. A sash holder for insertion between a side rail of a window sash and beads of a window frame, said holder comprising a strip of resilient sheet metal bowed longitudinally for the major portion of its length and having straight end portions of appreciable length extending from ends of the bowed portion at an angle thereto and provided with anchoring teeth spaced outwardly from ends of the bowed portion, the angle between the straight end portions and ends of the bowed portion causing depressing pressure upon the bowed portion to transform said bowed portion into a reverse curve defining an inwardly curved intermediate sash-engaging portion merging into outwardly curved portions at the junctions of the initially curved portion with inner ends of the straight end portions.
